CASE FOR RITUALISTIC APRONS AND THE LIKE

Filed April 7, 1950

21 INVENTOR.
BY Paul J. Ihling
John A. Earl

ATTORNEY.

UNITED STATES PATENT OFFICE

2,555,694

CASE FOR RITUALISTIC APRONS
AND THE LIKEPaul J. Ihling, Kalamazoo, Mich., assignor to
Ihling Bros. Everard Co., Kalamazoo, Mich.

Application April 7, 1950, Serial No. 154,691

8 Claims. (Cl. 190—41)

1

This invention relates to improvements in case for ritualistic aprons and the like.

The main objects of this invention are:

First, to provide a case for ritualistic aprons and the like which is compact and portable and supports the aprons effectively to prevent wrinkling or creasing and soiling thereof.

Second, to provide a case of this character which permits the aprons being quickly arranged therein and removed therefrom and which is of large capacity in proportion to its size.

Objects relating to details and economies of the invention will appear from the description to follow. The invention is pointed out in the claims.

A preferred embodiment of the invention is illustrated in the accompanying drawings, in which:

Fig. 1 is a front perspective view of a structure embodying my invention, the front of the outer closure member being partially broken away to disclose its relation to other parts and certain structural details.

Fig. 2 is a fragmentary end elevational view partially in vertical section on a line corresponding to the broken line 2—2 of Fig. 1, a number of aprons being conventionally illustrated.

Fig. 3 is a fragmentary front perspective view with the casing partially opened, aprons being indicated in supported position.

Fig. 4 is a front perspective view with the casing fully opened.

Ritualistic aprons are commonly of quite expensive material, such as lamb skin or chamois, and bear symbols or ornaments and their neat attractive appearance is marred by wrinkles or creases or if they become soiled. The embodiment of my invention illustrated is adapted to receive and effectively support and protect a plurality of such aprons.

The embodiment of my invention illustrated in the accompanying drawing comprises a plate-like base member 1 of suitable length and width for the size and number of aprons to be stored. End uprights 2 are secured to the base preferably with their outer sides flush with the ends of the base as is illustrated. These uprights are in this embodiment of a width corresponding to the width of the base. The end uprights are further supported by top and bottom cross rods 3 and 4 which are arranged near the rear edges of the uprights, a front bottom crossbar 5 being arranged near the front edges of the uprights. The upper ends of the uprights have recesses 6 there-in adapted to receive ties 7 of aprons 8 arranged

between the uprights and in front of the top crossbar as is illustrated in Fig. 3.

The uprights have vertically spaced V-shaped recesses 9 and 10 in their front edges, the adjacent edges 11 of these recesses being parallel and spaced to provide snubbing arms or members 12 around which the ties may be wrapped as is shown in Figs. 2 and 3. The V-shaped recesses provide hand openings above and below these snubbing arms which permits the wrapping of the ties, preferably a plurality at one time, around the snubbing arms, the hand grasping the ties being passed through the recesses.

To completely enclose the aprons or other objects supported as described I provide a casing preferably formed of a suitable grade of canvas or other fabric. This casing comprises a back panel 13 which is secured to the rear edge of the base 1 and to the rear edges of the uprights by means of headed tacks 14. The casing is provided with end panels 15 extending from the end edges of the back panel and having inner front closure flaps 16 extending from their front edges. The end panels have top flaps 17 on their upper edges foldable inwardly over the uprights and onto the aprons supported between the end members. One of the end flaps is shown turned outwardly in Fig. 3.

The front inner closure flaps 16 are provided with coacting zipper fastening elements 18 on their vertical edges, the zipper slide being indicated at 19. These inner closure flaps are notched at 20 to receive eyes 21 projecting forwardly from the base. The casing is provided with a top panel 22 extending from the upper end of the back panel and with an outer front closure panel 23 connected to the front edge of the top panel. The outer closure 23 is adapted to fold downwardly over the inner closure flaps 16. The closure 23 in the embodiment illustrated is provided with a rod 24 slidable in a suitable pocket 25 provided therefor and engageable and disengageable by sliding adjustment with the eyes 21 on the base.

A top board or plate 26 is mounted on the inner side of the top panel 22 preferably by means of straps 27 which are stitched to the back panel and outer closure member at 28 so that this top plate is swingably connected to the back panel 10 of the casing to permit its being swung back as shown in Fig. 4 to completely expose the apron supporting parts for convenient mounting and dismounting of the aprons.

A handle 30 is secured at 31 to the top panel 55 and the top plate, the details of attaching of the

handle to the top plate not being illustrated. By attaching the handle to the top plate the load on the casing is well distributed and the casing is not pulled out of shape when the structure is carried by means of the handle. Spherical feet 32 are also provided.

With this arrangement of parts I provide a structure in which the aprons are very effectively supported and protected and at the same time the structure is quite light in weight. It may be used as a shipping and storage container although when used in shipping it is desirable to wrap or enclose in a carton to prevent the casing becoming soiled and to permit proper marking for shipping without disfiguring the casing.

I have illustrated and described my invention in a highly practical embodiment thereof. I have not attempted to illustrate or describe other embodiments or adaptations as it is believed that this disclosure will enable those skilled in the art to embody or adapt my invention as may be desired.

Having thus described my invention, what I claim as new and desire to secure by Letters Patent is:

1. In a case for ritualistic aprons provided with ties and for similar articles, the combination of a base, end uprights corresponding in width to the width of the base and mounted thereon with their outer sides flush with the ends of the base, said uprights having recesses in their upper ends to receive said apron ties and having forwardly opening vertically spaced V-shaped recesses in their front edges, the adjacent edges of the recesses being parallel providing central forwardly projecting snubbing arms on which the apron ties may be wound for suspending the aprons by their ties in side by side relation between the uprights, top and bottom cross rods extending between said uprights, the top cross rod being disposed adjacent the rear edges of the uprights so that the aprons may be suspended in front thereof; a flexible casing comprising a back panel secured at its bottom and side edges to the rear edges of said base and said upright, end panels connected to the side edges of the back panel and having inwardly foldable top flaps at their upper ends, and having inner closure flaps on their front edges, said inner closure flaps being provided with coacting fastening elements on their vertical edges, a top panel connected to the upper edge of the back panel and closable over said top flaps, and an outer closure panel connected to the front edge of said casing top panel and closable over said inner closure flaps; said outer closure having an attaching rod at the bottom thereof, and said base being provided with eyes with which said rod is engageable to retain the outer closure in closed position.

2. In a case for ritualistic aprons provided with ties and for similar articles, the combination of a base, end uprights, said uprights having recesses in their upper ends to receive said apron ties and having snubbing arms on which the apron ties may be wound for suspending the aprons by their ties in side by side relation between the uprights; a flexible casing comprising a back panel secured at its bottom and side edges to the rear edges of said base and said upright, end panels connected to the side edges of the back panel and having inwardly foldable top flaps at their upper ends, and having inner closure flaps on their front edges, said inner closure flaps being provided with coacting fastening elements on their vertical edges, a top panel con-

nected to the upper edge of the back panel and closable over said top flaps, and an outer closure panel connected to the front edge of said casing top panel and closable over said inner closure flaps; said outer closure having an attaching rod at the bottom thereof, and said base being provided with eyes with which said rod is engageable to retain the outer closure in closed position.

3. In a case for ritualistic aprons provided with ties and for similar articles, the combination of a base, end uprights corresponding in width to the width of the base and mounted thereon with their outer sides flush with the ends of the base, said uprights having recesses in their upper ends to receive said apron ties and having forwardly opening vertically spaced V-shaped recesses in their front edges, the adjacent edges of the recesses being parallel so as to provide central forwardly projecting snubbing arms on which the apron ties may be wound for suspending the aprons by their ties in side by side relation between the uprights, and top and bottom cross rods extending between said uprights, the top cross rod being disposed adjacent the rear edges of the uprights so that the aprons may be suspended in front thereof.

4. In a case for ritualistic aprons provided with ties and for similar articles, the combination of a base, end uprights corresponding in width to the width of the base and mounted thereon with their outer sides flush with the ends of the base, said uprights having recesses in their upper ends to receive said apron ties and having forwardly opening recesses in their front edges spaced to provide forwardly projecting snubbing arms on which the apron ties may be wound for suspending the aprons by their ties between the uprights, and a flexible casing comprising a back panel secured to said base and uprights, end panels connected to the side edges of the back panel and having inner closure flaps on their front edges provided with coacting fastening elements on their adjacent vertical edges, a top panel connected to the upper edge of the back panel and closable over said top flaps, and an outer closure panel connected to the front edge of said casing top panel and closable over said inner closure flaps and provided with means for detachable connection to said base.

5. In a case for ritualistic aprons provided with ties and for similar articles, the combination of a base, end uprights, said uprights having recesses in their upper ends to receive said apron ties and having snubbing arms on which the apron ties may be wound for suspending the aprons by their ties between the uprights, and a flexible casing comprising a back panel secured to said base and uprights, end panels connected to the side edges of the back panel and having inner closure flaps on their front edges provided with coacting fastening elements on their adjacent vertical edges, a top panel connected to the upper edge of the back panel and closable over said top flaps, and an outer closure panel connected to the front edge of said casing top panel and closable over said inner closure flaps and provided with means for detachable connection to said base.

6. In a case for ritualistic aprons provided with ties and for similar articles, the combination of a base, end uprights corresponding in width to the width of the base and mounted thereon, said uprights having recesses in their upper ends to receive said apron ties and having forwardly opening recesses in their front edges spaced to

provide forwardly projecting snubbing arms on which the apron ties may be wound for suspending the aprons by their ties between the uprights, top and bottom cross rods extending between said uprights, the top cross rod being disposed adjacent the rear edges of the uprights so that the aprons may be suspended in front thereof, and an enclosing casing.

7. In a case for ritualistic aprons provided with ties and for similar articles, the combination of a base having end uprights, upper ends of said uprights receiving said apron ties, said uprights having snubbing members on which the apron ties may be wound for suspending the aprons by their ties between the uprights; a flexible casing comprising a back panel secured at its bottom and side edges to said base and said upright, end panels connected to the side edges of the back panel and having inwardly foldable top flaps at their upper ends, and having inner closure flaps on their front edges provided with coacting fastening elements, a top panel connected to the upper edge of the back panel and closable over said top flaps, and an outer closure panel connected to the front edge of said casing top panel and closable over said inner closure flaps; said outer closure having an attaching rod at the bottom thereof, and said base being provided with eyes with which said rod is engageable to retain the outer closure in closed position.

8. In a case for ritualistic aprons provided with ties and for similar articles, the combination of a

base having end uprights, upper ends of said uprights receiving said apron ties, said uprights having snubbing members on which the apron ties may be wound for suspending the aprons by their ties between the uprights; and a flexible casing comprising a back panel secured at its bottom and side edges to said base and said upright, end panels connected to the side edges of the back panel, and having inner closure flaps on their front edges provided with coacting fastening elements, a top panel connected to the upper edge of the back panel and closable over said top flaps, and an outer closure panel connected to the front edge of said casing top panel and closable over said inner closure flaps and provided with means for detachable connection to the base.
